UNITED STATES PATENT OFFICE.

THOMAS CLARKSON, OF LONDON, ENGLAND.

STEAM GENERATOR OR WATER HEATER.

Application filed December 31, 1925, Serial No. 78,671, and in Great Britain January 16, 1925.

This invention relates to steam generators or water heaters of the kind comprising an annular water chamber from which closed-ended water tubes or thimbles radiate inwards into a heating space through which hot gases flow from an inlet passage, liquid fuel burner or other source of heat at one end of the generator or water heater to an outlet at the other end thereof.

10 The object of the invention is to provide a generator of the above type in which the transference of heat from the hot gases or products of combustion to the water will tend to be improved.

15 According to this invention a central outlet is provided for the hot gases at the upper end of the steam generator or water heater and a substantially cylindrical baffle or plug is arranged centrally in the heating space with its wall adjacent to the ends of the thimbles so as to cause substantially all the hot gases to flow over and between the thimbles. The baffle or plug may be formed either partially or wholly of refractory material or may be formed entirely of metal. Further the baffle may be either rigidly or loosely supported solely by a rod or the like extending from a bridge piece at the top of the generator or may in addition rest at its lower end upon a suitable support.

20 Where the lower end of the plug or baffle is also supported this portion may be formed of a refractory metal or other refractory material and the upper portion of ordinary metal, these two portions being connected together in any convenient manner, while where the plug is supported either rigidly or loosely only from the top of the generator, it may be formed wholly either of ordinary metal or refractory material.

25 In some cases the baffle or plug may be provided with one or more passages through which air can be led into the combustion space. If desired, a superheater coil may be provided and such a coil, instead of being arranged concentric with the water space as hitherto, may be disposed above the closed-ended water tubes and preferably so 30 as to extend into a cover or dome secured to the top of the generator. In this construction the gas outlet is conveniently arranged in the side of the dome and a central aperture is provided in the dome through which 35 the plug can be withdrawn, this aperture

normally being closed by a cover plate from which the plug is suspended.

Where a superheater coil is provided as above described, the upper portion of the heating space of the generator may be 40 slightly reduced in diameter where it surrounds the superheater coil, while where no superheater coil is provided that portion of the heating space which lies above the thimbles is conveniently considerably reduced 45 in diameter so as to form a central outlet passage for the gases communicating with an outlet pipe and through which the plug can be withdrawn when desired.

50 The gases may be led into the base of the generator through a substantially helical passage so that they are caused to circulate round the plug or baffle as they pass through the heating space. The helical circulation above the base may be assisted by staggering the thimble tubes to form helical or 55 spiral paths for the gases.

60 The invention may be carried out in various ways but four alternative constructions of generator according to this invention are 65 illustrated somewhat diagrammatically by way of example in the accompanying drawings, in which

70 Figure 1 is a vertical section through the longitudinal axis of one construction of generator in which the baffle is formed partially of refractory material and partly of metal,

75 Figure 2 is a similar view to Figure 1 of an alternative form of generator in which a superheater coil is provided,

80 Figure 3 is a vertical section through the longitudinal axis of another alternative form of generator in which no superheater coil is provided, and

85 Figure 4 is a similar view to Figure 3 of another form of generator in which air can be fed to the combustion space through the plug or baffle.

90 In the construction illustrated in Figure 1, the generator comprises an annular water chamber built up from two cylindrical members A, A¹ connected at their ends by suitable end plates A² and A³. The inner member A¹ carries a series of closed-ended conical water tubes or thimbles B projecting 100 radially inwards from the member A¹ into a central heating space through which the hot gases or products of combustion are 105 adapted to flow, these tubes being sufficiently tapered to leave a space between them. The 110

tubes are also arranged in staggered relation, thus leaving helical passages therebetween. The inner member A^1 is conveniently reduced in diameter at its upper end as shown at A^4 to form an outlet passage for the gases.

The annular water chamber is supported on a base C which conveniently has a lining C^1 of refractory material and contains a 10 plug-like member D also preferably of refractory material and having a substantially helical guide surface or inlet passage D^1 for the hot gases entering the generator through a delivery pipe D^2 , a liquid fuel 15 burner also being provided, if desired, as indicated at D^3 . The helical passage or guide surface tends to cause the gases entering the generator to circulate round the central space as they pass through it. This 20 effect is aided by the staggered arrangement of the tubes, as previously described. The member D has a hollow conical boss D^4 adapted to form a support for and accommodate a spigot E^1 on the lower end of a 25 tubular baffle E mounted in the central space of the generator and of such diameter that its wall lies adjacent to the inner ends of the thimbles B . The tubular baffle E comprises a lower portion E^2 formed of refractory material and an upper portion E^3 formed of metal. The lower end of the upper portion E^3 fits over the upper end of the lower portion E^2 and is connected thereto by one or 30 more pins or the like E^4 . The upper end of the tubular member E is formed conical and supported by a vertical bolt F one end of which engages a suitable plug E^5 in the upper end of the member E while the other end is secured to a bridge piece F^1 extending 35 across the upper end of the outlet passage A^4 .

A cylindrical baffle G is conveniently disposed in the water space so as to extend around substantially the whole of that portion of the inner cylindrical member A^1 in which the thimbles B are disposed and thus assist in the circulation of water which will tend to pass up inside the baffle G and down outside it. When the apparatus is intended 45 for use as a steam generator, a perforated steam collecting pipe G^1 is conveniently disposed in the upper end of the steam and water space as shown.

In the alternative construction illustrated 50 in Figure 2, the steam generator comprises inner and outer cylindrical members H H^1 connected at their ends by suitable flanges or the like so as to enclose an annular steam and water space. Closed-ended water tubes 55 or thimbles J project radially inwards from the wall of the inner member H^1 into a central heating space through which the hot gases are adapted to flow.

The upper portion of the inner member H 60 is slightly reduced in diameter as shown at

H^2 and a superheater coil K is disposed within this reduced portion and extends into a dome-like member H^3 mounted on the top of the generator. The dome-like member H^3 is provided with a lateral outlet H^4 for the gases and a central aperture normally closed by a removable cover L . Suspended from the cover L by a link L^1 is a cylindrical plug or baffle M adapted to lie in the central space between the ends of the thimbles J and thus cause the hot gases to flow over and between these thimbles. The internal diameter of the superheated coil K and the diameter of the aperture closed by the cover L are such as to permit the withdrawal of the plug M through the top of the dome H^3 . Disposed in the water chamber is a cylindrical baffle N adapted to assist the circulation of water in a similar manner to the baffle G , shown in Figure 1. Suitable steam collecting pipes N^1 are conveniently provided in the upper end of the steam and water space and a feed water pipe N^2 conveniently enters this space near its lower end.

In the construction illustrated in Figure 3, the steam generator or water heater comprises an annular water and steam chamber built up from two cylindrical members O , O^1 connected at their ends by suitable plates or the like O^2 , O^3 . The inner member O^1 carries a series of closed-ended tubes or thimbles P extending radially inwards into a central heating chamber through which the hot gases flow for example as shown in Figure 3 from a furnace chamber adapted for the burning of solid fuel and is reduced in diameter at its upper end above the thimbles, as shown at O^4 , to form an outlet passage for these gases. Disposed in the central space between the closed ends of the thimbles P is a cylindrical plug or baffle Q formed either of metal or of a refractory material and suspended by a rod Q^1 from a bridge piece Q^3 arranged across the upper end of the outlet passage O^4 . As in the constructions previously described, a baffle plate R is arranged in the annular water chamber to assist the circulation while a perforated steam collecting pipe R^1 is disposed in the upper end of the annular chamber when the apparatus is to be employed as a steam generator. An outlet pipe O^5 for the gases is conveniently secured to the top of the generator as shown.

The steam generator or water heater shown in Figure 4 is somewhat similar to that shown in Figure 3, and comprises inner and outer cylindrical members S , S^1 connected at their ends by members S^2 , S^3 to form an annular steam and water chamber. The inner member S^1 carries closed-ended water tubes or thimbles T radiating inwards into a central heating space through which the hot gases flow and is reduced at its upper end

as shown at S^4 to form an outlet passage for these gases.

Disposed in the space between the closed ends of the tubes T is a hollow cylindrical metal plug or baffle U suspended from a bridge piece U^1 by a tube U^2 through which air can be delivered to the interior of the plug U . The tube U^2 is bent at its upper end as shown as U^3 and passes through the wall of an outlet pipe S^5 for the hot gases from the generator while the lower end wall of the plug U is provided with one or more apertures U^4 through which air delivered to the plug through the tube U^2 can pass to the combustion space of the generator. In this instance the generator is shown as provided with a furnace chamber adapted for the burning of solid fuel, for example coal, the combustion of which will be assisted by the air admitted through the hollow plug.

A cylindrical baffle W is provided in the water space to assist circulation as in the previously described constructions and a perforated steam collecting pipe X is disposed in the upper end of the steam space, a perforated annular baffle or splash plate Y being also provided below the steam collecting pipe if desired.

Although the invention has been particularly described with reference to steam generators, it is to be understood that it may be applied to water heaters not intended to generate steam. Further, in a generator embodying either of the constructions or arrangements of baffle as illustrated in Figures 1, 2 or 3, the generator may be heated by a furnace in which solid fuel is burnt or heat may be supplied to the generator either by hot gases derived from some external source alone, for example the exhaust gases of an internal combustion engine, or by a liquid fuel burner or other direct source of heat alone, or means may be provided whereby heat may be delivered to the generator from these sources either alternatively or together. Where a liquid fuel or like burner is provided for use alternatively or in addition to some external source of heat, a cover plate may be provided adapted either to close the air inlet passage for the fuel burner, which remains in position, or to replace the fuel burner and thus close the aperture through which it normally projects.

It is to be understood that the details of construction may be varied according to the purpose for which the generator or water heater is intended or the source of heat employed without departing from this invention.

What I claim as my invention and desire to secure by Letters Patent is:—

1. A water heater comprising an annular water chamber surrounding a heating space through which hot gases are adapted to pass, closed-ended water tubes extending radially

inwards from the water chamber into the heating space, means for supplying heat to the heating space adjacent to its lower end, a central outlet for the hot gases at the upper end of the heater, a bridge piece extending across this outlet, a substantially cylindrical baffle disposed centrally within the heating space with its wall adjacent to the ends of the water tubes and a supporting member for the baffle disposed coaxially therewith and connected at its lower end to the upper end of the baffle and at its upper end to the bridge piece.

2. A water heater comprising an annular water chamber surrounding a heating space through which hot gases are adapted to pass, closed-ended water tubes extending radially inwards from the water chamber into the heating space, means for supplying heat to the heating space adjacent to its lower end, a central outlet for the hot gases at the upper end of the heater, a bridge piece extending across this outlet, a substantially cylindrical baffle disposed centrally within the heating space with its wall adjacent to the ends of the water tubes and means for supporting the baffle comprising a member on which the lower end of the baffle rests and a rod like member disposed coaxially with the baffle and connected at its ends respectively to the upper end of the baffle and to the bridge piece.

3. A water heater comprising an annular water chamber surrounding a heating space through which hot gases are adapted to pass, closed-ended water tubes extending radially inwards from the water chamber into the heating space, means for supplying heat to the heating space adjacent to its lower end, a central outlet for the hot gases at the upper end of the heater, a bridge piece extending across this outlet, a substantially cylindrical baffle disposed centrally within the heating space with its wall adjacent to the ends of the water tubes, the lower end of this baffle being formed of refractory material, and means for supporting the baffle comprising a refractory base on which the lower end of the baffle rests and a rod like member disposed coaxially with the baffle and connected at its ends respectively to the upper end of the baffle and to the bridge piece.

4. A water heater comprising an annular water chamber surrounding a heating space through which hot gases are adapted to pass, closed-ended water tubes extending radially inwards from the water chamber into the heating space, a refractory member within the base of the heater, a helical guide surface formed in this refractory member, means for delivering hot gases on to this guide surface whereby the gases will tend to circulate around the axis of the generator in addition to passing therethrough over the water tubes, a central outlet for the hot gases at

the upper end of the heater, and a substantially cylindrical baffle disposed centrally within the heating space with its wall adjacent to the ends of the water tubes whereby substantially the whole of the hot gases passing through the heater will be caused to flow over and between the water tubes.

5. A water heater comprising an annular water chamber surrounding a heating space through which hot gases are adapted to pass, closed-ended water tubes extending radially inwards from the water chamber into the heating space, a refractory member within the base of the heater, a helical guide surface formed in this member, means for delivering hot gases on to this guide surface whereby the gases will tend to circulate around the axis of the heating space in addi-

tion to passing therethrough over the water tubes, a central outlet for the gases at the upper end of the heater, a bridge piece extending across this outlet, a substantially cylindrical baffle disposed centrally within the heating space with its wall adjacent to the ends of the water tubes, the lower end of this baffle resting on the refractory member at the base of the heater, and means for supporting the upper end of the baffle comprising a rod like member disposed coaxially with the baffle and connected at its ends respectively to the upper end of the baffle and to the bridge piece.

In testimony whereof I have signed my name to this specification.

THOMAS CLARKSON.
